UNITED STATES PATENT OFFICE.

FREDERICK R. SEIDENSTICKER, OF WEST MERIDEN, CONNECTICUT,
ASSIGNOR TO BRADLEY AND HUBBARD, OF SAME PLACE.

DESIGN FOR LAMP-BRACKET.

Specification forming part of Design No. 7,539, dated July 14, 1874; application filed June 3, 1874.
[Term of Patent 7 years.]

CASE A.

To all whom it may concern:

Be it known that I, FREDERICK R. SEIDENSTICKER, of West Meriden, in the county of New Haven and State of Connecticut, have invented a new Design for Lamp-Bracket; and I do hereby declare the following, when taken in connection with the accompanying illustration and the letters of reference marked thereon, to be a full, clear, and exact description of the same, and which said illustration constitutes part of this specification, and represents a perspective view.

This invention relates to a design for bracket for supporting a lamp or other burner; and consists in the peculiar configuration of the base and arm, together or separately, as more fully hereinafter described.

The base is a raised diamond form, with a floriated edge, as shown.

The bracket is of floriated curved form, one

branch, B, starting from a circular boss, C, at the base, and running into the principal arm A, a similar boss, D, to represent the cock, and terminates at the lamp-rest in a horizontal beaded bar, E, and section of Grecian key F, all as shown.

I claim as my invention--

1. The design for base for lamp-bracket, consisting of the raised diamond form with floriated border, as shown and described.
2. The design for lamp-bracket, consisting of the floriated curved arm A, one branch, B, starting from a circular boss at the base, and the whole terminating at the lamp-rest in the beaded bar, as shown and described.

FREDERICK R. SEIDENSTICKER.
